UNITED STATES PATENT OFFICE.

EDWIN F. HULBERT, OF MILWAUKEE, WISCONSIN, ASSIGNOR, BY MESNE ASSIGNMENTS, TO THE MASTER PACKAGE CORPORATION, OF DELAWARE.

TUBE-WINDING APPARATUS.

Application filed June 22, 1925. Serial No. 38,765.

To all whom it may concern:

Be it known that I, EDWIN F. HULBERT, a citizen of the United States of America, and resident of Milwaukee, in the county of Milwaukee and State of Wisconsin, have invented new and useful Improvements in Tube-Winding Apparatus, of which the following is a description, reference being had to the accompanying drawings, which 10 are a part of this specification.

The invention relates to tube winding machines, and more particularly to machines for winding paper, fibre or wood veneer sheets upon one another to form the body or 15 siding of a container.

One of the objects of the invention is to provide a method and apparatus for winding the tubing into a step-wound shell, preferably in multiple, whereby one end of the 20 siding is provided with an interior shoulder to take the end closure and the other end of the siding is of reduced outside diameter to take the siding of the cover of the container.

A further object of the invention is to provide a tube winding machine in which the 25 material taken from the supply roll is cut to the desired length, is coated with adhesive, is slit or cut to the desired width, and is wound to finished form on a mandrel; these 30 various steps being carried out by apparatus so combined and coordinated as to be under the control of a single operator.

The invention further consists in the several features herein described and more particularly defined by claims at the conclusion 35 hereof.

In the drawings: Fig. 1 is a side elevation view of the cutting mechanism and the feed therefor, parts being broken away;

40 Fig. 2 is a detail sectional view through the cutting mechanism, taken on the line 2—2 of Fig. 4;

Fig. 3 is a detail sectional view taken on the line 3—3 of Fig. 4;

45 Fig. 4 is a front elevation view of the cutting mechanism, parts being broken away and parts being shown in section;

Fig. 5 is a detail plan view of the feed mechanism associated with the cutter, parts 50 being broken away and parts being shown in section;

Fig. 6 is a front elevation view of the adhesive-applying mechanism;

55 Fig. 7 is a side elevation view of the adhesive-applying mechanism;

Fig. 8 is a section taken on the line 8—8 of Fig. 6;

Fig. 9 is a detail sectional view taken on the line 9—9 of Fig. 6;

Fig. 10 is a composite sectional view taken 60 along the broken line 10—10 of Fig. 8;

Fig. 11 is a view, partly in elevation and partly in section, of the slitting mechanism;

Fig. 12 is a detail sectional view taken on the line 12—12 of Fig. 11 showing one of the 65 cutters raised;

Fig. 13 is a sectional view taken on the line 13—13 of Fig. 11, showing one of the cutters lowered;

Fig. 14 is a section taken on the line 14—14 70 of Fig. 13;

Fig. 15 is a section taken on the line 15—15 of Fig. 13;

Fig. 16 is a detail sectional view taken along either of the lines 16—16 of Fig. 11, 75 showing the clutch mechanism;

Fig. 17 is a side elevation view of the slitting mechanism and winding mechanism;

Fig. 18 is a vertical sectional view through the winding mechanism, taken on the line 80 18—18 of Fig. 17;

Fig. 19 is a detail sectional view taken on the line 19—19 of Fig. 18;

Fig. 20 is a detail view looking in the direction of the arrows 20—20 on Fig. 18 along 85 the line A—A;

Fig. 21 is a detail view looking in the direction of the arrows 21—21 on Fig. 18 along the line A—A;

Fig. 22 is a detail sectional view along the 90 line 22—22 of Fig. 18;

Fig. 23 is a detail sectional view through the drive shaft for the tube mandrel;

Fig. 24 is an elevation view of air control mechanism;

Fig. 25 is a section taken on the line 25—25 of Fig. 24;

Fig. 26 is a section taken along the line 26—26 of Fig. 11;

Fig. 27 is a section taken along the line 100 27—27 of Fig. 11;

Fig. 28 is a detail sectional view taken on the line 28—28 of Fig. 17;

Fig. 29 is a detail sectional view taken on the line 29—29 of Fig. 17;

Fig. 30 is a schematic view of the apparatus embodying the invention, with the control system therefor;

Fig. 31 is a detail enlarged view of parts 110 of the cutting mechanism;

Fig. 32 is a side elevation view of circuit closure mechanism included in the apparatus;

Fig. 33 is a front elevation view of this closure mechanism;

Fig. 34 is a detail view of the slitting and winding mechanism;

Fig. 35 is a plan view of the cut strip;

Fig. 36 is a perspective view of the winding cylinder and the tubing wound thereon, with parts broken away and parts shown in section;

Fig. 37 is a view, partly in section, of the finished tubing.

15 The apparatus includes cutting-off mechanism and means for feeding the roll material thereto, and this part of the machine is shown in Figs. 1 to 5, inclusive, of the drawings, in which the numeral 40 designates the frames having a sheet support 41 secured thereto, carrying the fixed cutter bar 42 which cooperates with the reciprocating knife bar 43 mounted on a frame 44 yieldingly held in an elevated position by 20 means of spring 45. The knife bar frame 44 is suitably guided in ways 44' on the frames 40 and is moved downwardly by cams 46 engaging with a part of said frame 44 and mounted on a shaft 47 which is 25 rotated at the desired time to cut the sheet 30 to the desired length.

Spaced frames 48 having bearing brackets 49 thereon receiving the arbor 50 carrying the supply roll 51. The sheets from this 35 roll pass between a guide roll 52 and spring-pressed fingers 53 pivoted on a shaft 54 and urged against the roll 52 by springs 55, and it then passes between feed rolls 56 and 57 to the cutter. The upper feed roll 56 40 has its shaft mounted in journals 58 which are urged downwardly by springs 59 so as to provide a yielding engagement between the rolls 56 and 57 and the material passing 45 between them. The lower roll 57 is continuously driven by the drive shaft 60, carrying drive pulleys 61, by suitable gearing comprising bevel gears 62 and 63, shaft 64 and bevel gears 65 and 66, the gear 66 being mounted on the shaft 57' for the roll 57.

50 A continuously driven pulley 67 is loosely mounted on the shaft 47 and is adapted to drive the same through a one revolution type pin clutch, including a pin 68 mounted in a hub 69 on said shaft and urged by a 55 spring 70 into a recess 71 in the hub of the pulley 67. Control of the pin 68 is effected by a wedge 72 engageable with said pin and normally moved downwardly by a spring 73 to move and hold said pin in an 60 operative position, and moved upwardly out of engagement with said pin by a solenoid 74 whose plunger 75 is connected to said wedge. As the solenoid is only energized for a sufficient length of time to release the 65 pin from the wedge, and immediately there-

after the wedge is returned by the spring to a position to move the pin 68 out of clutched engagement with the pulley, the pin 68 is engaged with the pulley to effect only a single rotation of the shaft 47 and is then withdrawn by the wedge when it moves around to a position in which the wedge acts on it. A drag brake 67' is associated with the hub of the pulley 67 to prevent 70 overrunning.

75 At the time of cutting the feed is interrupted by the raising of the roll 56 by the turning of cams 76 on the shaft 56' for said roll, said cams cooperating with fixed surfaces 77 (see Figs. 5, 30 and 31). When the flats of said cams are engaged with the surfaces 77, as in Fig. 31, the rolls 56 and 57 are in feeding relation, and when the shaft 56' is oscillated to the position shown in Fig. 30, the rolls are held in separated non-feeding position. To effect the oscillation of the shaft 56' the shaft 47 carries a knocker arm 78 which engages an arm 79 on the shaft 56' to effect a swinging of the same, as above described (seen Figs. 1, 4, 30 and 31). When the roll 56 has been swung to the position shown in Fig. 30, feed of the material is again resumed by the swinging of the shaft 56' back to the position shown in Fig. 31 by an arm 80 on the shaft 56' connected by a link 81 to the plunger 82 of a solenoid 83 which is energized to accomplish this movement.

80 The sheet S is forced by the feeding rolls 56 and 57 along an adjustable table 84, in the form of adjustable rack bars, not shown in detail but shown diagrammatically in Fig. 30, to the gumming or adhesive-applying mechanism. This mechanism, shown in detail in Figs. 6 to 10, inclusive, includes a coating roll 85 and feed rolls 86. The roll 85 receives adhesive or sizing from a tank 87 by means of feed rolls 88 and 89. The shafts 85' for the rolls 85 and the shaft 92 for the roll 89 are connected by gears 90 and 91, and the shaft 92 for the roll 89 carries a sprocket 93 connected by a chain 94 to a sprocket 95 on a shaft 96. The shaft 96 carries another sprocket connected by a chain 97 to sprocket 98 on a shaft 99. The shaft 96 is connected by gears 100 and 101 to a shaft 102 connected by gears 103 and 104 to the power shaft 60. The shafts 96 and 99 carry feed rolls 105. The rolls 105 and 86 are grooved and wire-feed belts 106 run in said grooves. A guide roll 107 cooperates with the front feed-roll 105 and a curved stationary guide 108 with the other roll 105 at the delivery end of this unit. Sheet guide fingers 109, mounted on lever arms 110 on a shaft 111, are used to deflect the sheet downwardly toward the delivery belts 106.

85 The feed of adhesive to the roll 85 is controlled by the adjustment of the roll 89 relative to the roll 88, the bearings 112 for the 90

shaft 92 of roll 89 being made adjustable for this purpose. The rolls 86 are carried in a frame 113 which has legs 114 slidably mounted in guideways 115 in the frame 116 of this unit, and a plate 117 is mounted on a support 118 adjustably pivotally mounted on the frame 113. The frame 113 is moved upwardly to bring the sheet into operative position relative to the roll 85 by means of an air cylinder 119 having a piston (not shown) mounted therein and connected to a piston rod 120 which is connected to transverse bars 121 of the frame 113. Introduction of air into the cylinder 119, below the piston, causes it to move the frame 113 upwardly to bring the sheet into a position to receive its coating from roll 85. The roll 88 is driven by the shaft 92 through gears 122 and 123.

With the above construction the cut sheet passes between the cooperative rolls 107 and 105, over the belts 106, rolls 86 and plate 117 and between the guide 108 and roll 105, and during its passage receives a coating of adhesive from the roll 85. The coating roll 85 is disposed above the material and is so proportioned as to allow its lower surface to be positioned well below the bath of adhesive material and the feed rolls 88 and 89 so that excess adhesive material from the ends of the coating roll is removed by scrapers 85', having trough-shaped shoulders, associated with the bath, and returned thereby by gravity to said bath.

From the adhesive-applying mechanism the sheet passes over a table 124 (Fig. 30) to the slitting mechanism, which is shown in detail (Figs. 11 to 17, inclusive, 26, 27 and 30). This mechanism includes an anvil roll 125 which may be driven either by an electric motor 126 or by the main power drive of the machine through either of two gearing connections and clutches 127. Each clutch, as shown in Fig. 16, comprises a notched disk 128 carried by the shaft 129 of the roll 125, and a clutch cylinder 130 which drives the disk 128 through balls 131 mounted in the notches 132 of said disk. For the motor drive the cylinder 130 is formed integral with a gear 133 meshing with a gear 134 or a shaft 135 carrying a worm wheel 136 meshing with a worm 137 on a shaft 138 driven through suitable gearing 139 by the shaft of the motor 126. For the machine drive the other clutch cylinder 130 is formed integral with a gear 140 connected through a gear train 141, 142, 143, 144, to a shaft 145 driven from the shaft 164 through sprocket 235, chain 234 and sprocket 146. This anvil roll cooperates with cutters 147 to slit or cut the sheet lengthwise as it passes between said cutters and roll.

As shown more particularly in Figs. 11 to 15, each of the cutters 147 is in the form of a roller mounted on a bar 148 slidably mounted in a guide frame 149 having a gib connection 150 with the main frame 151, said frames 149 being slidable along the frame 151 for adjusting the spacing and being secured thereto in any suitable manner. Each cutter is yieldably pressed to its work by a spring 152 interposed between the top of the bar and an adjusting screw 153 on the frame 151. In order to raise the cutters from the work, each cutter bar is provided with an arm 154 engageable with a cam 155 on a manually-operable, transversely disposed shaft 156. For step winding, as shown in Fig. 36, the cutters are arranged in pairs and the cams 155 are so arranged that the turning of the shaft 156 brings one cutter of each pair to an operative position and raises the other cutter of that pair. To turn the shaft 156 a hand-lever 157 is mounted thereon, the shaft being held in adjusted position by a notched quadrant 158 and a hand-operated spring-pressed detent 159 associated with the lever 157. With this construction the slit portion W of the sheet material which is not to be wound is deflected downwardly after leaving the cutters, as shown in Fig. 36, by rollers 160, each mounted on an arm 161 of the cutter bar 148 and in a plane to one side of the cutter.

After the slitting operation the sheet, now cut into several sheets of lesser width, is fed direct to the tube-winding mechanism. The tube-winding mechanism, shown more particularly in Figs. 17 to 25, inclusive, and 28 to 30, inclusive, includes a frame 162 and a winding drum or mandrel 163 mounted on a shaft 164. This shaft is journalled in relatively fixed bearings 165 and 166 at one end, while at the other end it is supported by a removable bearing, as shown in Figs. 17, 18, 28 and 29, in the form of a bearing bracket 167 provided with a journal pin 168 fitting in the journal cap 169 in said shaft and having its lower end threaded to engage a feed screw 170 mounted to turn on a stud shaft 171 and carrying a handle 172, said bracket being held against lateral movement by fixed guide lugs 173. A drive pulley 174 is loose on the shaft 164 and is adapted to be drivingly connected thereto by a clutch, including a disk 175 slidably keyed to said shaft and clutch plates 176 between said disks and a clutch surface 177 on said pulley. The shaft 164 is of hollow tubular construction, closed at its ends to form a suction pipe, provided with openings 178, 179 and 180, registering respectively with a chamber 181, a space 182 within the clutch, and a conduit 183 within a lock-block 184 communicating with a pipe 185 leading to a space 186 within the mandrel. A tubular

member 187, whose ends are suitably sealed against air leakage, surrounds the rear end of the shaft 164 and forms the chamber 181 which is connected by a pipe 188 with a vacuum or suction air pump, not shown.

The mandrel 163 is provided with a series of alined perforations 189, and when the edge of the sheet or sheets to be wound is placed over these perforations the suction 10 created by the air pump connected to the pipe 188 will draw this edge or those edges against the mandrel and cause it to adhere thereto so that the winding of the sheet may be started.

15 In step tube winding the perforations 189 only come where they are in a position to be covered by the respective sheets to be wound.

The disk 175 has an annular flange 190 slidably mounted on a similar flange 191 on the pulley 174, and these flanges, with the sides of the disk 175 and pulley 174, form the space 182. The disk 175 is normally held out of pressure engagement with the plates 176 by springs 192 mounted in the space 182 between said disk and a collar 193 fixed to the shaft 164. When, however, the sheet to be wound has covered the holes 189, the increased suction is communicated to the space 182 and thus causes the disk 175 to move toward the pulley 174 against the action of the springs 192 and thereby press the plates 176 between them, and thus establish a driving relation between the power-driven pulley and shaft 164, thus revolving the mandrel which then winds up the sheet or sheets upon it into the completed tubing, the adhesive being applied to these sheets after the first turn 40 around the mandrel. As soon as the winding operation is completed, the opening of a relief valve 194 breaks the vacuum in the pipe 188 and thereby releases the pulley 174 from driving connection with the shaft, since the springs 192 then move the disk 175 out of pressure engagement with the clutch plates and the tube is no longer held to the mandrel by suction, so that the moving out and swinging down of the bearing bracket 167 permits the removal of the tube 50 from the mandrel.

In order to press the newly wound layer upon the previously wound layers, I provide a presser roller 195 disposed parallel to the mandrel 163 and journaled on a shaft 196 carried by the uprights 197 of a supporting frame, which uprights are vertically slidably mounted in guideways 60 198 on the frames 162 and are connected at their lower ends by a transverse frame member 199. Tappet blocks 200 carry rollers 201 running on cams 202 on a shaft 203 and are connected to the frame member 65 199 by springs 204, said blocks having holes

205 in which guide screws 206, carried by said frame member, are slidably mounted. Thus, the upward movement of said tappet blocks 200, by the cams, causes an upward movement of the roller 195 toward the 70 mandrel; and the springs 204 permit a downward movement of said roller 195 and its supporting frame as the thickness of the tubing increases.

For turning the shaft 203 to oscillate the 75 cams 202, I provide a gear 207 meshing with a rack 208 on the rod 209 of a compressed-air-operated piston 210 working in a cylinder 211, whereby the admission of air into said cylinder causes a translation 80 of the piston rod 209 in a direction to turn the shaft 203 to bring the high part of the cams 202 under the rollers 201 and thus move the pressing roller to an operative 85 position, the air pressure in the cylinder being maintained during the winding operation.

In order to stop the mandrel in a feeding position, the block 184 is provided with a locking recess 212 engageable with a locking bolt 213 having a rack face 214 meshing with a gear 215 on a shaft 216 carrying a grooved wheel 217 to which a cable 218 is secured and passes over a part thereof and carries a weight 219 which, when permitted to do so, acts to turn the shaft 216 so as to move the locking bolt 213 into a position for locking engagement with the block 184. The release of the bolt 213 is effected by a vacuum cylinder 220 connected by a pipe 221 with the pipe 188 and having a piston 222 working therein with its rod forming part of said bolt. Thus, when the vacuum line is established by the closing of valve 194 and the sealing of the holes 189, by the sheets, the bolt 213 is withdrawn and the clutch is engaged and the mandrel is free to be driven.

In order to effect the admission of compressed air to the cylinders 119 and 210, I provide a valve 223 controlling the admission of compressed air from the supply line 224 (Fig. 30) to the piping 225 and 226. The piping 225 connects with the head ends 115 of each of said cylinders so as to introduce compressed air therein to move the pistons to effect the upward movement of the plate 117 and the feed roll 195, while the piping 226 connects with the other ends of said 120 cylinders to effect a return movement of the pistons and the parts associated therewith.

The valve 223, shown in detail in Figs. 23 and 24, includes a casing 227 in which a rotary disk valve 228 works. This disk 228 is keyed to the shaft 216 and is held to its seat by pressure within the space 229 connected with the supply line 224. At the front of the casing are passages 230 and 231, with which the pipes 225 and 226 connect,

and an exhaust passage 232. The valve 228 has a transfer passage 233 in its front face, designed to establish communication between either of the passages 230 and 231 and the exhaust 232, while the other passage is connected with the pressure line. With this construction, when the shaft 216 is turned to release the bolt 213 the valve 228 is turned to bring the port 230 into communication with the supply line 224 and the transfer passage 233 then connects passage 231 with passage 232, whereupon the adhesive-applying mechanism is rendered operative and the presser roller 195 is moved to operative position. When the shaft 216 is turned by the weight 219 and the bolt 213 moved to locked position, the valve 228 is turned to bring the port 231 into communication with the supply line 224 and the transfer passage 233 then connects passage 230 with the passage 232, whereupon the pressure roller 195 is lowered to an inoperative position and the plate 117 likewise lowered.

23 The power drive for the shaft 145 is effected by a chain 234 connecting the sprocket 146 with a sprocket 235 on the shaft 164 so that the drive for the anvil roll 125 is co-ordinated with the drive of the winding mandrel 163 during the actual winding operation. The drive for the roll 125 from the motor 126 is used only for bringing the sheet to a position to start winding and the clutch 127 for the power drive slips during this operation and thereafter the clutch for the motor drive slips when the machine drive is in operation.

40 The complete control of the machine may be affected by a single operator from his station adjacent a switch box 236 (Fig. 17) at the winding end of the machine, where he is within reach of the valve 194, the lever 157, and the lever 167.

45 The circuit connections for the control of the solenoids 83 and 74 and the motor 126 are shown in Fig. 30, in which the numeral 237 designates the current supply line, and conductor 238 connected with one side of this line forms part of a control circuit.

50 A conductor 239 connects the conductor 238 with a motor-starting switch 240 and is put in circuit by a push-button switch 241. This conductor has a coil portion 244 for moving the switch arm 245 and is connected to the other side of the line. When the switch 241 is closed the switch 240 is operated to supply current to the motor 126 from the line 237 through switch arm 245, rheostat 246 and conductor 247.

55 A push-button switch 248 connects the conductor 238 with a conductor 249 leading to the electric magnet 250 of an electro-magnetically-operated switch 251, the current returning to the line through a conductor 252. Closing a switch 248 energizes

the magnet 250 and closes switch 251 so that current from the line passes through a conductor 253 through switch 251 to energize the coil of the solenoid 74 and returns by conductors 254 and 252 to the line. This 70 energization of solenoid 74, it will be recalled, causes the engagement of the pin clutch and the operation of the shear or cutter 43.

A push-button switch 255 connects the conductor 238 with a conductor 256 leading to the electromagnet 257 of an electro-magnetically-operated switch 258, the current returning to the line through conductors 259 and 252. Closing switch 255 energizes the 75 magnet 257 and closes switch 258 so that current from the line and conductor 253 passes through a conductor 260 and the switch 258 to energize the coil of the solenoid 83 and returns by way of conductors 261, 259 and 252 to the line. This energization of the solenoid 83 causes the release of the feed roll 56 so that it is free to move down into contact with the sheet from the roll 51.

90 In order to readily cut the material from the roll 51 into sheets of the desired length, I provide a portable circuit closure that may be placed in any position along the table 84. As shown in Figs 32 and 33, this closure comprises a base 262, a standard 263, a plate 264 carried by said standard, a fixed contact 265 and a movable contact 266 suitably insulated. The contact 266 is mounted on a member 267 pivoted on the plate 264 and having a part 268 adapted to be engaged by a knocker 269 also pivotally mounted on said plate and having a depending finger 270 adapted to be struck by the advancing edge of the sheet, which causes an upward swing of the finger 270 which in turn causes the knocker 269 to engage the part 268 and move the member 267 to bring the contact 266 into engagement with the contact 265 and then pass by said member 267 and swing back down over the sheet whose edge is higher and has then progressed slightly in advance of the finger 270. This closure is associated with the shear control circuit by conductors 271 and 272 and acts in the same way as the switch to produce a brief energization of the solenoid 74 to withdraw pin 75 and permit one operation of the shear 43 and its position upon the table 84 will, of course, determine the length of the sheet cut from the roll.

110 Referring now to Fig. 30, the general operation of the machine is as follows: The sheet S from the roll 51 is worked through between the roller 52 and the fingers 53 and between the feed rolls 56 and 57. With the circuit closure, including contacts 265 and 266, set at the desired position on the table 84, the operator, at his station, depresses push-button 255, closing the circuit to the solenoid 83, causing feed roll 56 to move 120

down to engage the sheet, and the power of the machine being on, the sheet is moved along the table until its advancing edge strikes the fingers 270 causing the contact 266 to engage contact 265, thereby energizing the circuit for the magnetic switch 250 and hence energizing the solenoid 74, causing the shear 43 to descend and cut off the sheet between it and the fixed blade 42, and during the cutting operation causing the disengagement of the feed roll 56 from the sheet, in the manner previously described. The operator then brings the cut sheet forward and places its advancing edge between the rolls 107 and 105 of the adhesive-applying mechanism and the sheet is then carried by the belts 106 over the plate 117, thence over the delivery belts 106 and between the guide 108, and roller 105 to the table 124, along which it is fed by the movement of the belts 106 until its advancing edge comes over the anvil roll 125, and its forward edge is then moved to bring it between the winding mandrel 163 and the presser roll 195. One set of cutters 147 having been depressed so that as the sheet passes over the roll 125, strips W are cut out of it and the sheet becomes a series of sheets of lesser width which are simultaneously wound up on the mandrel 163. As previously explained, during the starting of the winding operation the motor 126 is put into operation by the closing of the push button switch 241 to provide a preliminary feed of the sheet past the slitters or cutters to bring the advancing edges into position adjacent the holes 189 in the mandrel 163. As soon as the advancing edge, or edges, covers these holes the vacuum in line 188 (the valve 184 being closed) causes the lock bolt 213 to be withdrawn; causes the clutch, including drive pulley 174, to be thrown in; and hence a winding of the sheets upon the mandrel. Simultaneously with the release of the lock bolt 213 the valve 223 is operated, admitting compressed air from the pipe 24 to the cylinders 210 and 119, thereby respectively causing the presser roll 195 to move up into pressing engagement with the sheet as it is being wound on the mandrel 163, and causing the plate 117, with the rollers 86 and belts 106, to be moved up toward the adhesive-applying roll 85, thereby causing this roll to deposit a coating of adhesive onto the sheet as it passes between this roll and its support.

The first layer of the sheet or sheets that is wound up on the mandrel 163 has no adhesive applied to it, and this is brought about by the preliminary feed of the sheets from the adhesive-applying mechanism to the mandrel 163 prior to the elevating of the plate 117 and the spacing of the adhesive-applying mechanism at a distance equal to the circumference of the mandrel. In order to accommodate mandrels of different sizes

the spacing of the adhesive-applying mechanism is made adjustable, as will be noted from Figs. 7 and 8, by the provisions of gear wheels 273 mounted on shafts 274 on the frame members 116 engaging with racks 275 on the floor. The supporting table or rack between the cutter and the coating mechanism, while not shown in detail, is also made adjustable to accommodate different spacings between these units. As soon as the sheet or sheets have been wound up on the mandrel the operator opens the valve 194 and this, as previously explained, releases the locking bolt 213 and causes a release of the clutch 174—175 and operates the valve 223 so as to cause the compressed air to be introduced into the opposite ends of cylinders 210 and 119 from that previously described, thereby respectively depressing the presser roller 195 and the support, including the plate 117, rolls 86 and belts 106 of the adhesive-applying mechanism. Under these conditions the tubing may be taken off from the mandrel 163 on the release and turning down of the bearing 167.

It will be observed that the anvil roll 125 is spaced a relatively short distance from the point at which the sheet or sheets is or are led in between the winding mandrel 163 and the presser roll 195, and this distance is so close that the sheet material does not have a chance to buckle or slip from the time it leaves the cutters 147 and is wound up on the mandrel. This method of cutting the material immediately adjacent the mandrel enables me to produce a step-wound shell, which is shown in Figs. 36 and 37. In winding this type of shell my method is as follows: One of each pair of the sets of cutters 147 (Fig. 11) is depressed to cooperate with the anvil 125 and as the sheet passes between them it is cut into a series of sheets of lesser width which are simultaneously wound up on the mandrel, to the desired thickness, thereby producing the part 276 of the shell. Then these cutters are raised and the other cutters of each pair are depressed to cooperate with the anvil and another sheet passes between these cutters and is cut into a series of sheets of lesser width, which are wound up on the last layer of the previously wound part 276, to the desired thickness, forming a part 277 which, owing to the spacing of the cutters, is displaced from that of the previously wound part 276 so that the finished shell, shown in Fig. 37, has an annular internal shouldered portion 278 at one end to take the end closure of the container and an end portion 279 of less thickness than the main body 125 of the shell with a shoulder 280 which takes the siding of the cover of the container. The various layers of the sheet material aline themselves on the winding mandrel as the sheet is not permitted to buckle or bend 130

after leaving the cutters 147. By using a number of sets of cutters on a relatively wide sheet of material, I am able, by this method, to produce a plurality of step-wound shells on the mandrel 163 at one time, as shown in Fig. 36.

I desire it to be understood that this invention is not to be limited to any particular form or arrangement of parts except in so far as such limitations are specified in the claims or necessitated by the prior art.

What I claim as my invention is:

1. The method of producing step-wound shells, in multiple, which consists in cutting the sheet into a series of sheets of lesser width, winding these sheets upon a mandrel into a series of tubes, then cutting another sheet into a series of sheets whose edges are displaced from the edges of the previously wound sheet, and winding these sheets upon the previously wound tubes to produce a series of finished step-wound shells, the cutting of the sheets being done immediately adjacent the winding mandrel to prevent buckling of the sheets after cutting and insuring the aligning of the adjacent layers of each tubular part of the shell.

2. In a tube-winding machine, the combination with a winding mandrel, of cutting mechanism disposed adjacent thereto, including a series of cutters arranged in spaced pairs, means for moving one of each pair of cutters into cooperative relation with the sheet to cut the same prior to its being wound on the winding mandrel, means for raising the first-mentioned set of cutters to bring the other cutters of each pair into operative relation with the sheet prior to its being wound on the mandrel, whereby some of the sheets wound on the mandrel are displaced relative to the others to form a step-wound shell, means for pressing the layers of adjacent sheets together as they are wound up on the mandrel, and means for applying adhesive to the sheets prior to winding around the mandrel.

3. In a tube-winding machine, the combination with an adhesive-applying mechanism, including an adhesive-coating roll, a sheet-supporting means movable to bring the sheet to a position to receive a coating of adhesive from said roll, a winding mechanism including a winding mandrel and a pressing roll, and fluid-pressure-operated mechanism for simultaneously applying and releasing said pressing roll and said sheet-supporting means.

4. In a tube-winding machine, the combination of a mandrel upon which the sheet is wound, a pressing roll cooperating with said mandrel, said mandrel having perforations and a suction space connected to a suction line whereby the closure of said perforations by said sheet causes suction to hold the advancing edge of the sheet to the man-

drel, means for locking the mandrel in a position to receive the advancing edge of the sheet, including a locking member, a compressed-air-operated motor for moving the pressing roll to operative position relative to the mandrel, and valve mechanism controlling the supply of compressed air to said motor operable on the operation of said locking member.

5. In a tube-winding machine, means for feeding material from the supply roll to a cutting mechanism, cutting mechanism for cutting the material into sheets of the desired length, adhesive-applying mechanism for coating the cut sheets, slitting mechanism for dividing the coated sheet into a plurality of sheets of lesser width, winding mechanism receiving the sheets from the last-mentioned cutting mechanism to wind them into tubing, an operator's station adjacent the winding mechanism, and means for controlling the feeding mechanism and the first-mentioned cutting mechanism from the operator's station.

6. In a tube-winding machine, the combination with the tube-winding mechanism including a winding mandrel and means for applying adhesive to the material prior to winding, of means for cutting the material to the desired length, and an electric control for said cutting means including switch mechanism actuated by the advancing sheet material to render said cutting means operative.

7. In a tube-winding machine, the combination with the tube-winding mechanism including a winding mandrel and means for applying adhesive to the material prior to winding, of means for cutting the material to the desired length, an electric control for said cutting means including switch mechanism actuated by the advancing sheet material to render said cutting means operative, feed mechanism associated with the cutting mechanism, means for rendering said feed mechanism inoperative during the operation of the cutting mechanism, and an electric control for said feed mechanism including a switch operated by the operator from a position adjacent the winding mechanism.

8. In a tube-winding machine, the combination with the tube-winding mechanism, the adhesive-applying mechanism, the cutting mechanism and the feeding mechanism associated with the cutting mechanism, of electrical control for said feeding and cutting mechanisms operable from a position adjacent the winding mechanism, fluid-pressure-operated means rendering said adhesive-applying mechanism operative, and means actuated by the operation of said tube-winding mechanism for rendering said fluid-pressure-operated means operative.

9. In a tube-winding machine, the com-

- 3 combination of a revoluble mandrel provided with suction, sheet-holding means, means for locking the mandrel in a predetermined feed position, driving means for the mandrel 5 including a suction-operated clutch thrown in by the attachment of the sheet to the mandrel, and suction-operated means for releasing said locking means consequent to the attachment of the sheet to the mandrel.
- 10 10. In a tube-winding machine, the combination with an adhesive-applying mechanism, including an adhesive-coating roll, a sheet-supporting means movable to bring the sheet to a position to receive a coating 15 of adhesive from said roll, winding mechanism including a winding mandrel and a pressing roll, means including a locking member for holding the mandrel in a predetermined position, a compressed-air-operated motor for moving the pressing roll to operative position relative to the mandrel, a compressed-air-operated motor for moving the sheet-supporting means to operative position adjacent the adhesive-coating roll, 20 and valve mechanism controlling the supply of compressed air to said motors operable on the operation of said locking member.
11. In a tube-winding machine, the combination with the winding mechanism, sheet dividing mechanism and adhesive-applying mechanism, of a main drive shaft for the machine, a power drive means for driving the dividing mechanism from said power 25 drive during the winding operation, and an electric motor operatively connected to drive said dividing mechanism prior to the winding operation.
12. In a tube-winding machine, the combination with the winding mechanism, of means for supplying a plurality of sheets to said winding mechanism, comprising slitting mechanism for cutting a single sheet into a plurality of sheets of lesser width, 30 said slitting mechanism comprising a plurality of cutters, each cutter comprising a knife member and its support, and a cam shaft provided with cams cooperating with said supports for selectively raising or lowering said cutters, and means under the control of the operator for turning said shaft to operate said cams.
13. In a tube-winding machine, the combination of tube-winding mechanism including a winding mandrel and a presser 35 roll associated therewith, of suction-operated, sheet-holding means associated with said mandrel, means for driving the mandrel automatically rendered operative by the placement of a sheet upon the mandrel, 40 and means automatically rendered operable substantially simultaneously with the drive for the mandrel for moving said pressing roll to an operative position against the sheet on the mandrel.
14. In a tube-winding machine, the combination with a winding mandrel, of slitting mechanism associated therewith whereby a sheet supplied to the slitting mechanism is cut into a number of sheets of lesser width 45 and wound up on the winding mandrel, said slitting mechanism comprising adjustable cutters whereby a second set of tubes is superimposed upon the first set of tubes wound on the mandrel but in a lengthwise 50 offset relation relative thereto to form a plurality of step-wound shells, means for applying adhesive to the material prior to winding it on the mandrel, and means for pressing successive layers of the material 55 together during the winding operation.
15. In a tube-winding machine, the combination with a winding mandrel, of cutting mechanism disposed adjacent thereto including a series of cutters arranged in spaced pairs for cutting the sheet into a plurality of spaced sheets prior to their being wound on the winding mandrel, and means associated with said cutters to deflect that portion of the cut sheet between 60 the spaced sheets downwardly and out of the winding plane of said mandrel.
16. In a tube-winding machine, the combination with a winding mandrel, of cutting mechanism disposed adjacent thereto including a series of cutters arranged in spaced pairs for cutting the sheet into a plurality of spaced sheets prior to their being wound on said mandrel, means for raising and lowering the cutters, and a roller 65 associated with the cutters and moving up and down therewith and disposed in advance of and to one side of the cutter with which it is associated and below the plane of this cutter to deflect the cut out portion 70 of the sheet downwardly and out of the winding plane of said mandrel.

In testimony whereof, I affix my signature.

EDWIN F. HULBERT.
